ERWIN & COMPANY, OF CHICAGO, ILLINOIS, A CORPORATION
OF ILLINOIS.

AUTOMATIC SWITCH MECHANISM.

No. 838,090.

Specification of Letters Patent.

Patented Dec. 11, 1906.

Application filed January 13, 1906. Serial No. 295,856.

To all whom it may concern:

Be it known that I, AUGUSTUS C. DURDIN, Jr., a citizen of the United States, residing at Chicago, county of Cook, and State of Illinois, have invented new and useful Improvements in Automatic Switch Mechanism, of which the following is a specification.

My invention relates to improvements in automatic switch mechanism for opening and closing an electric circuit between a generator and an electric motor, and the same is especially adapted to be used in connection with a reservoir of a water-supply system.

The object of my invention is to provide a simple and efficient switch to be used either upon or in connection with a water-reservoir, into which water is forced under pneumatic pressure by a force-pump which is driven with an electric motor, the construction being such that when the water and air in the reservoir have reached a predetermined pressure the electric circuit communicating between the generator and the motor will be automatically opened, when the motor will cease to run until the water in the reservoir has been partially exhausted, and thereby brought to a lower predetermined pressure, when the switch will be reversed and the electric circuit automatically closed, whereby the motor will resume and continue its work until the higher predetermined pressure is again attained and whereby the supply of water in the reservoir may be thus automatically maintained without the personal attention of an attendant.

My invention pertains more especially, however, to the peculiar mechanism employed for communicating a quick positive movement to the circuit-closing switch in either direction from a slowly-moving diaphragm which is actuated by the pressure in the reservoir.

The construction of my invention is explained by reference to the accompanying drawings, in which—

Figure 1 represents a front view thereof. Fig. 2 is a top view; and Fig. 3 represents a rear view, part broken away to show the interior.

Like parts are identified by the same reference characters throughout the several views.

1 represents a diaphragm-chamber, which

may be either connected directly with the water-reservoir or the pipes leading to or from the same by the duct 2, whereby it will be understood that as the pressure in the reservoir is increased or diminished the diaphragm will be raised and lowered thereby, when motion will be communicated from the diaphragm, as hereinafter described, to the switch mechanism.

For convenience of construction I preferably support the switch mechanism directly upon the diaphragm-chamber, in which case the supporting-standard 3' is preferably cast integrally with the upper side of the diaphragm-chamber.

4 represents the switch-bar, which is pivotally supported at its center from the standard 3' on the bolt 5 and is adapted to contact at its respective ends with the terminals 6 when in the position shown in Fig. 1, whereby the electric circuit is closed between the electric generator and the motor, (not shown,) and the motor thereby is set in motion until the desired pressure is reached in the reservoir. When the desired predetermined pressure has been reached in the reservoir, the switch will be reversed and thrown from the position shown to that indicated by dotted lines, whereby the electric motor will be caused to stop until the water-supply has, as previously stated, been partially exhausted, when the switch will be again thrown in contact with the terminals, and thus the pressure in the reservoir will be automatically maintained.

Motion is communicated from the diaphragm 3 to the switch-bar 4 in one direction as the pressure in the reservoir is raised through the diaphragm-plate 7, reciprocating rod 8, pivot 9, lever 10, pivot 11, reciprocating bar 12, pivot 13, link 14, trunnion 15, lever 16, and lever-supporting pivot 5, which lever-supporting pivot 5 extends laterally through the standard 3' and serves as a support for said switch-bar 4, which is rigidly fixed to the front end of said pivot. When, however, the pressure in the diaphragm-chamber has diminished, said diaphragm is forced in the opposite direction by the recoil of the spiral spring 17, and the movement of all said parts is reversed and the electric circuit closed, as previously described.

The spiral spring 17 surrounds the recipro-

cating rod 8 and is interposed between the nut 18, which has screw-threaded bearings 19 on said rod, and the stationary bracket 20, which is rigidly fixed to or formed integrally with the standard 3'. Said bracket 20 also serves the further purpose of a guide-bearing for the upper end of said rod 8. Thus it will be obvious that when the diaphragm 3 is forced upwardly by the pressure from the reservoir' said spiral spring 17 will be compressed, and when the pressure in the reservoir is diminished the diaphragm will be forced downwardly by the recoil of said spring. It will also be obvious that the tension of said spring may be increased by turning the nut 18 toward and against the spring and diminished by turning said nut in the opposite direction, whereby the device may be adjusted so as to act when the water in the reservoir has reached any predetermined pressure desired. For example, if the elevation to which the water is being forced is such that fifty-pounds pressure in the reservoir is required to carry the water to the desired elevation the nut 18 will be turned toward the spring until the tension of the same will require a pressure of fifty pounds to the square inch in the diaphragm-chamber before the switch mechanism will be moved. When, however, a less pressure will serve the desired purpose for raising the water to the desired elevation, the nut 18 will be turned in the opposite direction upon the rod 8, whereby the tension of the spring is diminished and the switch mechanism will be actuated by a less pressure. Thus by turning the nut 18 upwardly and downwardly upon the supporting-rod the apparatus may be adjusted so as to actuate the switch mechanism, as stated, at any desired predetermined pressure.

It will be understood that as the rod 8 is raised the lever 10 will be carried upwardly from the point shown to that indicated by dotted lines in Fig. 3, whereby the bar 12 and the inner end of the link 14 will also be moved upwardly from the position shown to that indicated by dotted lines in said figure, whereby the spiral spring 21, carried by said link 14, will be compressed between the shoulder 22 of said link and the trunnion 15, through which the upper end of said link 14 passes.

It will be understood that the action of the spiral spring 21 against the trunnion 15 will have a tendency to hold the lever 16 rigidly in place against the stop 23 until the pivot 13 has passed the longitudinal center of said lever 16, as indicated by dotted lines in said Fig. 3, and that as soon as said link has passed the longitudinal center of said lever 16 the recoil of said spiral spring 21 will act in the opposite direction upon the outer end of said lever 16, whereby said lever 16 will be thrown with a quick positive movement from the position shown against the stop 23 in the opposite direction to the position indicated by

dotted lines in said figure against the stop 24, whereby the switch-lever 4, which is rigidly fixed upon the outer end of said pivot 5, will be thrown from a position shown in Fig. 1 to that indicated by dotted lines in said figure and out of contact with the electric terminals, whereby the electric motor will cease to run, as previously described.

It will now be understood that assuming that the lever 16 is in the lower position, (indicated by dotted lines in Fig. 3,) it will remain in such position until the pressure beneath the diaphragm has been reduced and said diaphragm and the parts connected therewith have been moved downwardly or in the opposite direction by the recoil of said spiral spring 17 and the inner end of said link 14 brought below the longitudinal center of said lever 16 at the point shown in said Fig. 3, when said lever 16 will be thrown upwardly from the position indicated by dotted lines to that shown by the recoil of said spiral spring 21, whereby the switch-lever 4 will be again brought in contact with the electrical terminals 6, as shown in Figs. 1 and 3, when the electric circuit will be thereby closed and the motor will again resume its work.

It will be obvious that by the device described for actuating the lever 16 the same will be retained at rest during the movement of the link 14 until the inner end of said link has passed the longitudinal center of said lever 16 in either direction and that when said link has passed the longitudinal center of the lever said lever will be moved with a quick positive movement in either direction, whereby the switch-bar, which is rigidly fixed to the protruding end of the same pivotal support which carries said lever 16, will also be moved with a quick positive movement and the liability of said moving parts becoming stopped on their centers or at any intermediate point between the extreme limits of their movements is avoided, whereby the motor will always act promptly and positively. The lower end of the reciprocating bar 12 is preferably retained in place by antifrictional roller 25, which roller is pivotally supported from the standard 3' by the bolt or screw 26.

It will of course be understood that the generator (not shown) is connected with the binding-screws 26 26 by electrical conductors in the ordinary way and that the electric motor is connected with the binding-screws 27 27 by electrical conductors in the ordinary way and that consequently the circuit will be closed between the electric generator and the motor through the conductors 28 28, terminals 6 6, plates 29 29, and conductors 30 30, whereby as soon as the plates 29 are brought in contact with the terminals 6 the electric circuit will be closed on both sides of the circuit.

The trunnion 15 is pivotally connected with the lever 16 by the pin 31, whereby said

trunnion is free to turn as the outer ends of the link which pass through the same is moved upwardly and downwardly. A loose sleeve 32 is preferably interposed between the upper 5 end of the spiral spring 17 and the bracket 20 for the reception of the upper end of said spring.

While I have shown and described my switch mechanism in connection with a diaphragm and diaphragm-chamber, it is obvious that the same is equally adapted to be used in connection with a piston and cylinder. The form shown, however, is preferred.

Having thus described my invention, what
15 I claim as new, and desire to secure by Letters
Patent, is—

1. The combination with the terminals of an electric switch of an electric switch-bar and a pivotally-supported lever, means connected with said switch-bar for closing and opening an electric circuit through said terminals, a diaphragm-chamber and vibratory diaphragm located in said chamber adapted to be actuated in one direction by fluid-pressure in said chamber and in the opposite direction by the recoil of a spring, means for increasing and diminishing the tension of said spring whereby the same may be adjusted to correspond with any desired predetermined pressure, means actuated by said diaphragm for communicating a quick positive vibratory movement in either direction to said pivotally-supported lever and from thence to said circuit-closing mechanism.

20 phragm-chamber, a vibratory diaphragm located in said chamber adapted to be actuated in one direction by fluid-pressure and in the opposite direction by the recoil of a spring, means actuated by said diaphragm for communicating a quick positive vibratory movement therefrom to said vibratory lever comprising a contact-bearing 7, reciprocating rod 8, vibratory lever 16, pivotally connected at one end with said rod 8 by the pivot 5 and 90 at its opposite end with a pivotally-connected trunnion 15, link 14, slidably connected at its outer ends with said trunnion 15 and pivotally connected at its opposite end with the reciprocating bar 12, bar 12, two-armed lever 95 10, said lever 10 being pivotally connected at one end with said bar 12 and at its opposite end with the rod-retaining bracket 20 and integrally connected between its respective

35 2. The combination with the terminals of
an electric switch of an electric switch-bar,
means connected with said switch-bar for
closing and opening an electric circuit through
said terminals, a vibratory diaphragm adapt-
40 ed to be actuated in one direction by fluid-
pressure from a water-reservoir and in the op-
posite direction by the recoil of a spring,
means for adjusting the tension of said spring
to correspond with any desired predetermined
45 pressure of the fluid against said diaphragm,
means actuated by said diaphragm for com-
municating a quick positive vibratory move-
ment in either direction to said switch-bar
comprising a lever rigidly fixed at one end to
50 the pivotal support of said switch-bar a link
having slidable bearings at one end on the
free end of said lever and pivotally connected
at its opposite end with a transversely-mov-
able bar whereby the pivotally-connected
55 end of said link is carried toward the longitu-
dinal center of said lever in one direction by
the action of said diaphragm and in the oppo-
site direction by the action of said spring, a
second spiral spring carried on said link inter-
60 posed between a shoulder formed on the inner
pivotal end of said link and the slidable bear-
ings on said vibratory lever, said spring be-
ing adapted to be compressed as said link is
drawn toward the longitudinal center of said

100 pivotally connected between its respective
ends to said reciprocating rod 8, spiral spring
21, interposed between the shoulder 22 of
said link 14 and said trunnion 15, means for
slidably guiding the free end of said bar 12 as
the same is moved upwardly and down-
wardly by the action of the diaphragm 3 and
spring 17, said spring 14 being adapted to be
compressed between the shoulder 22 and the
trunnion 15 as the pivotal end of said link ap-
proaches the longitudinal center of said lever
16 in either direction, said spring being adapt-
ed when the pivotal end of said link has
passed the longitudinal center of said lever 16
to recoil and throw said lever 16 in the oppo-
site direction whereby a quick positive move-
ment is communicated from the slowly mov-
ing diaphragm in either direction through the
mechanism described to said vibratory lever
16 from said vibratory lever through pivot 5
to the circuit-closing mechanism, all substan-
tially as and for the purpose specified.

vibratory lever in either direction and when 65 the inner pivotal end of said link has passed the longitudinal center of said vibratory lever in either direction, said spring is adapted by its recoil to throw said vibratory lever in the opposite direction with a quick positive 70 movement.

3. The combination with the terminals of an electric switch of a pivotally - supported switch - bar, means connected with said switch-bar for closing and opening an electric circuit through said terminals, a vibratory lever rigidly fixed at one end to the supporting-pivot of said switch-bar and adapted to communicate motion to said switch-bar as its free end is vibrated in either direction, a diaphragm-chamber, a vibratory diaphragm located in said chamber adapted to be actuated in one direction by fluid-pressure and in the opposite direction by the recoil of a spring, means actuated by said diaphragm for communicating a quick positive vibratory movement therefrom to said vibratory lever comprising a contact-bearing 7, reciprocating rod 8, vibratory lever 16, pivotally connected at one end with said rod 8 by the pivot 5 and 80 at its opposite end with a pivotally-connected trunnion 15, link 14, slidably connected at its outer ends with said trunnion 15 and pivotally connected at its opposite end with the reciprocating bar 12, bar 12, two-armed lever 95 10, said lever 10 being pivotally connected at one end with said bar 12 and at its opposite end with the rod-retaining bracket 20 and pivotally connected between its respective ends to said reciprocating rod 8, spiral spring 21, interposed between the shoulder 22 of said link 14 and said trunnion 15, means for slidably guiding the free end of said bar 12 as the same is moved upwardly and downwardly by the action of the diaphragm 3 and spring 17, said spring 14 being adapted to be compressed between the shoulder 22 and the trunnion 15 as the pivotal end of said link approaches the longitudinal center of said lever 16 in either direction, said spring being adapted when the pivotal end of said link has passed the longitudinal center of said lever 16 to recoil and throw said lever 16 in the opposite direction whereby a quick positive movement is communicated from the slowly moving diaphragm in either direction through the mechanism described to said vibratory lever 16 from said vibratory lever through pivot 5 to the circuit-closing mechanism, all substantially as and for the purpose specified. 110 115 120

In testimony whereof I affix my signature
in the presence of witnesses.
